UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

RHEOSTAT.

1,336,918.

Specification of Letters Patent. Patented Apr. 13, 1920.

Application filed August 28, 1919. Serial No. 320,448.

To all whom it may concern:

Be it known that I, ANTONIO PAPINI, a subject of the King of Italy, having resided in the United States one year last 5 past and having declared my intention of becoming a citizen thereof, residing in the city and county of Philadelphia, State of Pennsylvania, have invented a new and useful Rheostat, of which the following is a 10 specification:

My invention consists of a novel construction of a rheostat which is designed to control or furnish to lamps, motors or other electric apparatus any desired amount of 15 current from zero to the maximum available in the line, said rheostat being composed of a series of resistance elements, each one having predetermined ohmic resistance, said elements being preferably disposed in a circular or annular row, although it will be evident that they could be differently arranged and collocated if desired without departing from the principle of my invention.

My invention further consists of a novel 25 construction of resistance elements each of which is composed of an insulating refractory shell threaded at its ends and secured in operative position in any suitable manner, said shell being filled with resistance 30 material, such as mica flakes and graphite, or graphite and asbestos, or the like, commingled in suitable proportions according to requirements, there being located at the bottom of said resistance material a plug of 35 conducting material adapted to be compressed by means of a metal thimble of novel construction, which is threaded to the lower end of said shell, the amount of the compression determining or calibrating the 40 resistance, under which the current is adapted to drop.

It further consists of a novel collocation 45 of resistance elements held in position by a suitable frame, composed of top and bottom insulating plates held in assembled position by means of bolts or the like.

It further consists of a novel construction 50 of a control spindle of metal having a thumb piece of insulating material and provided with suitable bearings, and a metallic finger carrying at its end, a contact member, which is at all times under tension of a suitable spring, whereby the rotation of said finger and contact member, controls or furnishes to the desired point, any amount of

current from zero to the maximum available in the line.

It further consists of a novel construction of resistance elements, contact cups therefor, and a novel manner of resiliently 60 supporting said resistance elements.

It further consists of other novel features of construction all as will be hereinafter 65 fully described and particularly pointed out in the claims.

For the purpose of illustrating my invention, I have shown in the accompanying drawings one form thereof which is at present preferred by me, since the same will be found in practice to give satisfactory and 70 reliable results, although it is to be understood that the various instrumentalities of which my invention consists can be variously arranged and organized and that my invention is not limited to the precise arrangement and organization of these instrumentalities as herein shown and described.

Figure 1 represents a vertical, sectional elevation of a rheostat, embodying my invention, certain of the parts being shown in 80 elevation and the section being taken on line 1—1 Fig. 2.

Fig. 2 represents a top plan view of Fig. 1.

Fig. 3 represents a bottom plan view of Fig. 1.

Fig. 4 represents a diagram of the conductors and their adjuncts to be hereinafter referred to.

Similar numerals of reference indicate 90 corresponding parts.

Referring to the drawings,

1 designates my novel construction of rheostat, the same comprising a suitable framework having the top and bottom insulating plates 2 and 3, which are held in 95 position by the bolts 4, having the upper pair of nuts 5 and the lower pair of nuts 6 or similar fastening devices, the bottom plate 3 being provided with legs 7, which are preferably four in number, whereby my 100 novel device may be fastened to the wall or floor or any other desired point. The resistance elements 8 may be of any desired number and as each element is similarly constructed, a description of one will suffice 105 for all.

Each of said resistance elements is composed of a cylindrical insulating refractory shell 9 which is externally threaded at its lower and upper ends 10 and 11, respectively. 110

12 designates an upper thimble, which is internally threaded at its lower end so as to engage the contiguous exteriorly threaded portion 12 of the shell 9, said thimble being 5 of conducting material and preferably having the closed rounded top 13.

14 designates an asbestos gasket, which is interposed between the upper end of the shell 9 and the continuous wall or shoulder 10 of the thimble 12. The shell 9 is filled with resistance material 15, which is preferably in the present instance in the form of mica flakes and graphite, or graphite and asbestos, or the like, commingled in suitable proportions. Below the resistance material 15 is the plug 16 of any suitable conducting material, which is adapted to be compressed toward, against or into the resistance material 15 by means of the lower thimble 17, which is of metal and is internally threaded 15 to engage the lower exteriorly threaded portion 10 of the shell 9. The thimble 17 is provided with the upwardly projecting portion 18 which presses on the bottom of the plug 16, so that it will be apparent that the amount of compression of the resistance material 15, can be predetermined or calibrated by screwing the thimble 17 on or off the shell 9, to the desired extent. The bottom of the thimble 17 is preferably recessed or concaved as indicated at 19 and is supported upon or in contact with the head 20 of the supporting member which has the depending stem 21 which can slide freely 20 and has a limited play in the hole 22 of the bottom plate 3.

23 designates a spring interposed between the top of the plate 3 and the bottom of the head 20, whereby a cushioning action is obtained, by reason of the tension of the said spring, so that a proper contact is made between the head 20 and the recessed portion 19 of the thimble 17.

24 designates threaded holes in the upper plate 2, the latter being of insulating material, said threaded holes being arranged in circular order and receiving the contact cups 25 whose top surfaces are slightly above the top of the plate 2, so that it will be seen 45 that when the parts are assembled, the closed top 13 of the upper thimble 12 contacts with the underside of the contact cups 25 and that all the parts are properly and resiliently held in assembled position by the tension of the spring 23, since the stem 21, which said spring surrounds, is capable of a limited movement through or with respect to the bottom plate 3, as will be understood from 50 Fig. 1.

60 The contact cups 25 may be of any desired number and are arranged circularly or annularly as will be understood from Fig. 2, it being apparent that the number of said contact cups, as well as the number of the resistance elements 8, can be varied and

they may be differently disposed if desired or their number increased or diminished according to requirements.

26 designates a central spindle which is composed of metal and provided with the 70 knurled knob or thumb piece 27 of insulating material, said spindle turning on the sleeve or bearing 28, which is in threaded engagement with the top plate 2. The lower end of said spindle 26 has its bearing in the 75 spring clip 29, which is in the form of a split cup and is secured to the bottom plate 3 by any suitable fastening means, as a screw 30, the head of which bears upon the bottom of said clip 29, said screw passing 80 through the bottom plate 3 and serving as a binding post being held in position by a nut 31 or equivalent fastening device.

32 designates a collar which is located below the bottom of the bearing 28 and is 85 pinned to the spindle 26 by the pin 33, so that all the parts are at all times properly retained in assembled position.

34 designates a finger of metal which is secured to the spindle 26 so as to rotate in 90 unison therewith, the outer end of said finger having the upwardly extending stem 35 of the contact member 36 projecting therethrough, the bottom of said contact member riding over or resting upon one or the other 95 of the contact cups 25.

37 designates a spring having one end secured in fixed position by the screw 38 or the like upon the finger 34 while its free end 39 presses resiliently on the top of the stem 35, so that said contact member 36 is at all 100 times under the tension of said spring 37, which presses it downwardly whereby the requisite contact will at all times be made between said contact member and the desired contact cup 25.

It will be understood from the bottom view of the rheostat, seen in Fig. 3, that one pole or wire 40 is connected directly to the clip 29 through the medium of the screw 30 and the nut 31, which acts as a binding post for said pole, the other pole or wire 41 being connected to the annular copper washer 42 which connects electrically all of the members 21, so that the current coming 110 from the conductor 40 passes through the clip 29, the spindle 26, finger 34, contact pin 36 and contact cup 25 through a resistance element 8 and supporting member 20 to the annular washer 42, and the conductor 41, 115 to the lamps or apparatus and then back to the wire or conductor 43.

When the rheostat is in position of rest, see Fig. 2, and the diagram in Fig. 4, the contact member 36 is on insulating material 44 but when the rheostat is in operation, the finger 34 and its contact member are turned by the thumb piece 27, so that said contact member will rest on the element representing high resistance as 46 and can then be 120 125

moved in the direction of the arrow seen in said diagram until it reaches the position of no resistance, indicated at 45, whereupon the current will then pass in full.

5 The stroke of the finger 34 can be limited by means of a stop pin 47 whose position will be best understood from Fig. 2.

It will be apparent from that foregoing that by my novel construction, I have produced a novel rheostat which can be cheaply manufactured and will be durable, efficient and reliable and wherein all of the parts can be readily inspected for the purposes of inspection, replacement and repair, it being 10 apparent that any of the resistance elements 8 can be readily removed from the upper and lower connections and in case it is desired to replace any element or portion of the device it can be readily and expeditiously 15 done by unskilled labor.

The members comprising the resistance elements 8 are all made of standard or uniform dimensions, so that the parts are interchangeable and the varying amount of resistance desired in each element is attained 25 by screwing the thimbles 17 on or off the shells 9 so as to compress the resistance material 15 more or less according to requirements.

30 It will now be apparent that I have devised a novel and useful construction of a rheostat which embodies the features of advantage enumerated as desirable in the statement of the invention and the above description, and while I have, in the present instance, shown and described a preferred embodiment thereof which will be found in practice to give satisfactory and reliable results, it is to be understood that the same 35 is susceptible of modification in various particulars without departing from the spirit or scope of the invention or sacrificing any of its advantages.

Having thus described my invention, what 40 I claim as new and desire to secure by Letters Patent, is:—

1. In a rheostat, a plurality of resistance elements of different resistance, means for varying the resistance therein, tension devices for resiliently supporting said resistance elements, contact devices above said elements, and a movable contact member in resilient engagement with said contact devices.

2. In a rheostat, a resistance element, composed of a shell, an upper thimble thereon, resistance material in said shell, a lower thimble threaded to said shell, a conducting plug contained within said shell, intermediately of said lower thimble and said resistance material, whereby the rotation of said lower thimble varies the resistance, a resilient support for said lower thimble, and a contact device for said upper thimble.

3. In a rheostat, a plurality of resistance elements annularly arranged and supported,

conducting material therein, means for varying the resistance in said elements, tension devices for resiliently supporting said elements, contact cups above said elements, and a rotatable contact member in resilient engagement with said contact cups.

4. In a rheostat, a framework, a plurality of resistance elements annularly arranged thereon, tension devices bearing on the bottom of said elements, a rotatable spindle centrally arranged with respect to said elements, a finger carried by said spindle, a spring pressed contact member carried by said finger, and contact cups carried in said framework and alining with said resistance elements.

5. In a rheostat, a resistance element composed of a shell, an upper thimble threaded thereto, resistance material in said shell, a lower thimble also threaded to said shell, a conducting plug contained in said shell intermediately of said lower thimble and said resistance, whereby the rotation of said lower thimble varies the resistance, a resilient support for said lower thimble, a contact cup engaging said upper thimble, a movable contact member for closing the circuit with respect to said resistance element, and means for resiliently pressing said contact member into contact with said contact cup.

6. In a rheostat, a framework composed of upper and lower insulating plates, contact cups mounted in said plates, resistance elements having their upper ends seated in said contact cups and their lower ends resiliently supported, a contact member movably mounted with respect to said contact cups, and resilient means for pressing said contact member downwardly into contact with said cups.

7. In a rheostat, a framework composed of upper and lower nonconducting plates spaced apart and supported, contact cups in said upper plate, resistance elements below said contact cups, each of said elements comprising a shell, an upper thimble in engagement therewith and in contact with its alining cup, a lower thimble having an inwardly projecting portion and in threaded engagement with its shell, resistance material in said shell, a plug intermediate said resistance material and in contact with the inwardly projecting portion of said lower thimble, and resilient supports for said resistance elements.

8. In a rheostat, a framework comprising upper and lower insulating plates annularly arranged, contact cups seated in said plates, resistance elements also annularly arranged and having their upper ends alining with and in contact with said contact cups, resilient supporting means for the bottom of said resistance elements, a spring clip connected to said lower plate and having a

spindle seated therein, and a finger rotatable in unison with said spindle and carrying a contact member adapted to contact with said contact cups.

- 5 9. In a rheostat, a framework comprising upper and lower insulating plates, contact cups seated in said upper plate, resistance elements having their upper ends alining with and in contact with said contact cups, 10 resilient supporting means for the bottom of said resistance elements, the latter and said cups being annularly arranged, a spring clip connected to said lower plate and having a spindle seated therein, a finger located 15 above said upper plate and rotatable in unison with said spindle and carrying a contact member movably mounted in its outer end, and resilient means for pressing said contact member downwardly upon the top 20 of said contact cups.

10. In a rheostat, a framework composed of upper and lower insulating plates, contact cups seated in said plates and arranged in a circle, resistance elements in alinement 25 with said contact cups and in contact therewith, supporting members for the bottom of said resistance elements, said supporting members having stems passing through said lower plate and provided with upper heads 30 contacting with and supporting said resistance elements, springs intermediate said heads and bottom plate, an annular conducting washer connected to the lower ends of the circular row of supporting devices, 35 and means for closing an electric circuit with respect to a desired contact cup and resistance element.

11. In a rheostat, a framework composed of upper and lower insulating plates, contact cups seated in said plates and arranged in a circle, resistance elements in alinement 40 with said contact cups and in contact therewith, supporting members for the bottom of said resistance elements, said supporting members having stems passing through said bottom plate and provided with heads supporting said resistance elements, springs intermediate said heads and bottom plate, an annular conducting washer connected to the 45 bottom ends of the circular row of supporting devices, and means for closing an electric circuit with respect to a desired contact cup and resistance element, said means comprising a spring clip secured to the lower 50 of said plates, a spindle having its lower end rotatably mounted in said spring clip, a bearing for the upper portion of said spindle located in the upper of said nonconducting plate, a finger carried by said spindle, and 55 a contact member carried by said finger.

12. In a rheostat, a framework composed of upper and lower insulating plates, contact cups seated in said upper plate and arranged in a circle, resistance elements in 60 alinement with said contact cups and in con-

tact therewith, supporting members for the bottom of said resistance elements, said supporting members having means passing through said lower plate and provided with heads supporting said resistance elements, 70 springs intermediate said heads and lower plate, an annular connecting washer connected to the bottom ends of the circular row of supporting devices, means for closing an electric circuit with respect to a desired contact cup, said means comprising a spring clip secured to said lower plate, a spindle having its lower end rotatably mounted in said spring clip, a bearing for the upper end of said spindle located in said upper nonconducting plate, a finger above 80 said upper plate and carried by said spindle, a contact member movably mounted in said finger, and resilient means for pressing said contact member downwardly upon a contact 85 cup.

13. In a rheostat, a framework composed of upper and lower nonconducting plates suitably supported, a series of contact cups arranged in a circle and seated in the top of 90 said upper plate, an insulation element and an element of no resistance also circularly arranged in said upper plate, a series of resistance elements of varying resistance arranged in alinement with said contact cups, 95 a spindle arranged in the center of said circle of resistance elements, and contact devices carried by said spindle and adapted to be moved respectively from said insulation element to the highest resistance element 100 and thence to the elements of lower resistance to the point of no resistance.

14. In a rheostat, a framework composed of upper and lower nonconducting plates suitably supported, a series of contact cups 105 arranged in a circle and seated in the top of said upper plate, an insulation element and an element of no resistance also circularly arranged in said upper plate, a series of resistance elements of varying resistance arranged in alinement with said contact cups, 110 means for resiliently supporting the bottoms of said resistance elements, a spindle arranged in the center of said circle of resistance elements, and contact devices carried by said spindle and adapted to be moved respectively from said insulation element to the highest resistance element and 115 thence to the elements of lower resistance to the point of no resistance.

15. In a rheostat, a framework composed of upper and lower nonconducting plates suitably supported, a series of contact cups arranged in a circle in the top of said upper plate, an insulation element and an element 125 of no resistance also circularly arranged in said upper plate, a series of resistance elements of varying resistance arranged in alinement with said contact cups, means for resiliently supporting the bottoms of said 130

- resistance elements, a spindle arranged in the center of said circle of resistance elements, contact devices carried by said spindle and adapted to be moved respectively 5 from said insulation element to the highest resistance element thence to the elements of lower resistance to the element of no resistance, and a conducting annular washer secured to the lower portion of said resilient 10 supporting devices for said resistance elements.
16. In a rheostat, a framework composed of upper and lower nonconducting plates suitably supported, a series of contact cups 15 arranged in a circle in the top of said upper plate, an insulation element and an element
- of no resistance also circularly arranged in said upper plate to complete the circle of said cups, a series of resistance elements of varying resistance arranged in alinement 20 with said contact cups, supporting means for the bottom of said resistance elements, a spindle rotatably supported, a finger on said spindle, a contact device carried by said finger, and a stop for said finger adapted to 25 normally retain said contact device when inoperative upon said insulation element.

ANTONIO PAPINI.
